MECHANISM FOR TRAVERSING ARTILLERY
PIECES

Nathan S. Glassman, Washington, D. C.

Application May 6, 1947, Serial No. 746,283

2 Claims. (Cl. 89—41)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

This invention relates to mechanism for traversing an artillery piece, and provides traversing means for an improved gun mount which can be broken down into man pack loads for mobility. The particularly novel and useful features of the improved mechanism are the detachable traverse bar on demountable trails, the traverse arm on the rotatable, removable gun carriage, and the operative connecting means, for the bar and arm, slidable on the bar for both rough traversing and fine azimuth adjustment of the gun, by rocking the arm and carriage.

While there has been illustrated in the drawings and hereinafter fully described a specific embodiment of the invention, it is to be distinctly understood that the invention is not considered to be limited to said specific embodiment, and that its scope is defined by the claims appended hereto.

In the drawings:

Fig. 1 is a perspective of the improved mount supporting the piece and provided with the improved traversing mechanism, parts being broken away.

Fig. 2 is an enlarged vertical section, on the line 2—2 of Fig. 1, in the direction of the arrows, parts being broken away.

Fig. 3 is a vertical section on the line 3—3 of Fig. 2, in the direction of the arrows.

Fig. 4 is a horizontal section on the line 4—4 of Fig. 2, in the direction of the arrows.

Fig. 5 is an enlarged vertical section on the line 5—5 of Fig. 1.

As shown in the drawings, the improved traversing mechanism is applied to a gun mount having a ground-supported, circular base plate 1 with an integral, concentric, cylindrical, hollow pedestal 2 on which is mounted, as by welding, a crosshead 3 comprising a pair of tubular arms extending diametrically from pedestal 2, on the outer ends of which are removably pivotally connected trails 4 and 5, provided with collars 6 bolted thereon and having shackles 7 for attachment of eye 8 and hook 9 on the ends of a traverse bar 10, respectively. A latch 11 is pivoted on the shackle 7 engaged by hook 9 to retain hook 9 in engaged position.

The improved traversing means has a split-sleeve 12 slidable axially of bar 10. A split ring 13 is mounted on sleeve 12 by bolts 14, and has ears 15 in which are adjusting nuts 16 having

peripheral sockets 17 for set screws 18 threaded in ears 15. Nuts 16 are threaded on two reversely threaded coaxial bolts 19 on head 20 pinned in collar 21 of handle 22 for clamping and releasing ring 13 and sleeve 12 relative to bar 10. Sleeve 12 has a peripheral flange 23, spaced from ring 13, on which is seated one end of sleeve 24 about bar 10 and having peripheral flanges 25 and 26. A ring 27 is disposed loosely about ring 12 abutting flange 23 and has a flange 28, about the end of sleeve 24, abutting flange 25. Flange 28 is attached to sleeve 24 by bolt 29. Sleeve 24 has interior threads 30 with which mesh exterior threads 31 on a sleeve 32 freely slidable on bar 10. A ring 33 loosely about sleeve 32 is pinned to flange 26 of sleeve 24 by pins or screws 34. Sleeve 24, with rings 27 and 33 attached thereto, is rotatable about, but not axially movable of sleeve 12, and sleeve 12 and sleeve 24 are so related that when ears 15 are adjusted to release ring 13 and sleeve 12 from engagement with bar 10, sleeves 12 and 14 are slidable, as a unit, axially of bar 10, and meshing threads 30 and 31 cause sleeve 32 to move axially of bar 10 when sleeve 24 is either rotated or moved axially of bar 10.

Ring 13 has mounted thereon, by the bolts 14, a spring detent 35 co-acting with notches 36 in ring 27 to prevent accidental rotation of sleeve 24, and for indicating degrees of rotation of sleeve 24.

Sleeve 32 has diametrical lugs 37 on which are pivoted, by bolts 38, the ends 39 of a yoke 40 having a shank 41 slidably received in a tubular end portion 42 of a traversing arm 43 suitably attached to a post 44 suitably journaled in the hollow pedestal 2 of the base and supporting the rotatable top carriage of the mount. Suitable elevating mechanism 45 for the gun 46 is carried by the traversing arm 43.

A tubular housing 41 projects from the pedestal 2, under the arm 43, in which is slidable a latch 48 having a head 49 received in a notch 50 in the lower face of arm 43. Latch 48 is biased toward arm 43 by a coil spring 51 about latch 48 and confined between head 49 and a plug 52 screwed into the lower end of housing 47. A pair of cam plates 53, with an operating finger 54, are pivoted on the lower end of latch 48 and coact with the lower face of plug 52 to retract latch 48 to release arm 43 for traversing.

A bracket 55 is suitably mounted, adjacent the gun 46, on the carriage supporting gun 46. In the bracket 55, there is removably mounted a telescopic sight 56 so positioned that its line of sight is precisely parallel with the bore of gun 46. It will be noted (Fig. 1) that the parts are so

related that arm 43, gun 46 and sight 56 are constantly parallel and that the bracket 55 spaces the sight 56 laterally of the gun 46. The sleeve 32 for rocking arm 43 for traversing and the sleeve 24 for sliding the sleeve 32 are disposed constantly below the space between the gun 46 and the sight 56. This relation of the parts provides a very desirable feature of the improved mechanism, viz. the disposition of the manually operated, actuating sleeve 24, for traversing, in constant immediate juxtaposition with the sight 56. It is to be understood that the sight 56 is elevated above the ground the proper degree for the operator of the piece to apply his eye to the sight 56 while prone on the ground and sleeve 24 is so related to sight 56 as to be constantly disposed so as to be grasped, for operation, by the prone operator while his eye is applied to the sight 56.

The use and operation of the improved mount and traversing mechanism will now be described. With the trails 4 and 5 properly disposed relative to pedestal 2 and crosshead 3, and traverse arm 43 disposed normal to crosshead 3 and locked in position by latch 48, traverse bar 10 is placed parallel to crosshead 3, its eye 8 swinging in shackle 7, and hook 9 is engaged in its shackle 7 and retained therein by latch 11. Yoke 40 being properly disposed on bar 10 by adjustment of sleeves 12, 24 and 32, the shank 41 is inserted into the tubular portion 42 of the arm 43.

The mechanism is thus conditioned to traverse the gun 46. Latch 48 being retracted to release arm 43, the arm 43 is rocked by movement of sleeve 32 axially of bar 10. Sleeve 12 being released from bar 10, sleeves 12, 24 and 32 can be shifted bodily on bar 10 for rough traversing. When sleeve 12 is clamped on bar 10, sleeve 32 can be shifted axially of bar 10 by rotation of sleeve 24 for vernier setting.

It is obvious (Fig. 2) that when sleeve 12 is released from bar 10, traversing is accomplished by sliding sleeve 24 axially of bar 10. Sleeve 24 pinned to flange 28 shifts ring 27 which shifts sleeve 12 since its flange 23 fits between ring 27 and threads 30 in sleeve 24. Thus it is seen that for rough traversing sleeves 12, 24 and 32 move bodily on bar 10.

When the mechanism is adjusted for vernier setting, by clamping sleeve 12 to bar 10, the sleeve 24 is immovable axially of bar 10 because flange 23 on sleeve 12 is disposed between ring 27 and threads 30. Rotation of sleeve 24 causes meshing threads 30 and 31 to shift sleeve 32 axially of bar 10, since sleeve 32 is non-rotatable on bar 10 because of yoke 40 attached thereto. Telescoping of shank 41 and tubular portion 42 permits yoke 40 to travel axially of bar 10.

It is to be understood that during rough traversing, spring detent 35 engaged in one of the notches 36 restrains sleeve 24 against rotation. When sleeve 24 is rotated for fine azimuth adjustment, spring detent 35, acting as a "click" as it springs into successive notches 36, serves as an audible indicator of the degree of traverse, since it is to be understood that the parts are so designed that a precise degree of traverse of the gun is produced by rotation of sleeve 24 through the arc comprehended by a pair of notches 36. Suitable indicia may be placed on the traverse

bar 10 for determining the desired positions of sleeve 32 for rough traversing.

Having described the invention, what I claim is:

1. In a traversing mechanism for a gun mount having a rotatable gun carriage and a pair of adjustable trails, the combination of a traverse arm having one end mounted on the carriage and having a tubular portion at its other end; a traverse bar removably mounted on and connecting the trails; a sleeve slidable axially of said traverse bar; an adjustable clamp on said sleeve for fixing said sleeve on and releasing said sleeve from said bar, to prevent and permit movement of said sleeve axially of said bar; a second sleeve on said bar, and being interiorly threaded; a coupling for connecting said two sleeves, said second sleeve being rotatable in said coupling about said bar, immovable axially relative to said first sleeve, and movable with said first sleeve axially of said bar; a third sleeve slidable axially of said bar and having an exteriorly threaded portion received in said second sleeve, the threads of said second and third sleeves being meshed; and a yoke having its ends pivotally mounted on said third sleeve, and provided with a shank slidable in the tubular portion of said traverse bar.

2. In a traversing mechanism for a gun mount having a rotatable gun carriage, the combination of a rock arm mounted on the carriage; a slidable member reciprocable on the mount; a telescopic connection between said arm and said member for rocking said arm by reciprocation of said member; a rotatable member on the mount, threaded on said slidable member for reciprocating said slidable member by rotation of said rotatable member, said rotatable member having a plurality of notches symmetrically disposed on its periphery; and a spring detent so disposed on said mount that it springs into engagement and is forced out of engagement with successive notches, on rotation of said rotatable member, the character of the parts being such that audible clicks are produced by the successive engagements, the degree of traverse of the carriage precisely corresponding with the degrees of angular displacement of the rock arm which precisely correspond to the degrees of reciprocation of said slidable member which precisely correspond to the degrees of rotation of said rotatable member indicated by said clicks.
